FIG. 1

FIG. 2

FIG. 3

FIG. 4

FIG. 5

FIGURE 1 is a top plan view, of an astronaut's glove embodying my new design;

FIGURE 2 is a bottom plan view thereof, of the astronaut's glove of FIGURE 1 in which the glove is illustrated as being rotated, end over end;

FIGURE 3 is a side view, in elevation, of the glove, as viewed from the lower edge of FIGURE 1;

FIGURE 4 is an end view of the glove, as viewed along the line 4—4 of FIGURE 3; and

FIGURE 5 is an end view of the glove of this invention as viewed substantially along the lines 5—5 of FIGURE 3.

The dominant features of my design reside in the portions shown in solid lines.

I claim:

The ornamental design for an astronaut's glove, as shown and described.
